UNITED STATES PATENT OFFICE.

GEORGE F. CONNER, OF PORT HURON, MICHIGAN.

DESIGN FOR A ROAD-ROLLER WHEEL.

SPECIFICATION forming part of Design No. 33,141, dated August 28, 1900.

Application filed July 12, 1900. Serial No. 23,424. Term of patent 14 years.

To all whom it may concern:

Be it known that I, GEORGE F. CONNER, a citizen of the United States, residing at Port Huron, in the county of St. Clair and State of Michigan, have invented and produced a certain new and original Design for Road-Roller Wheels; and I do declare the following to be a full, clear, and exact description of the invention, such as will enable others skilled in the art to which it appertains to make and use the same.

The invention relates to a new and original design for a road-roller wheel; and it consists of a wheel of the shape and configuration shown in the accompanying drawings, in which—

Figure 1 is a perspective view of the wheel, and Fig. 2 is a side elevation.

The leading feature of the design comprises a wheel having a broad annular tread 1, a hub 2, radiating spokes 3, and an internal gear 4, secured to the inner side of the tread between its extreme inner edge and the radiating spokes and connected to or merging into an annular rib 5, projecting inwardly from the inner face of the wheel.

What I claim is—

The design for a road-roller wheel, as herein shown and described.

In testimony whereof I have hereunto set my hand in presence of two subscribing witnesses.

GEORGE F. CONNER.

Witnesses:

G. R. HAIGH,
E. C. AKERS.
